UNITED STATES PATENT OFFICE

SAMUEL F. ARBUCKLE, OF HIGHLAND PARK, MICHIGAN, ASSIGNOR TO MONOGRAM LENS CORPORATION, OF DETROIT, MICHIGAN, A CORPORATION OF DELAWARE

FIXED FOCUS HEAD LAMP

Application filed July 7, 1927. Serial No. 203,948.

This invention relates to headlights for automobiles and especially that type of headlight adapted to use a light bulb having two filaments in order to project two separate beams, one for fast driving, and the other for driving in traffic or parking.

Headlights are commonly in use in which a single filament bulb is mounted in a parabolic reflector, and an adjustment is provided whereby it may be moved both axially and vertically so that the filaments may be placed in exactly the proper position with respect to the focal point of the reflector so that the desired beams may be produced. This adjustment was found to be necessary because of the slight movement almost always found between the bulb and the socket, because of the tolerance in the manufacture of the electric light bulbs wherein the spacing of the filaments with respect to the envelope of the bulb varies slightly, in some instances about $3/64$ of an inch and because reflectors were used having a short focal length which made them very sensitive to variations of the light source. Hence, when a new bulb was inserted in a headlight, the filaments might be entirely out of place with respect to the reflector and necessarily had to be adjusted to obtain the proper result from the headlight. This adjustment of the bulb in the headlight has been found objectionable because of the fact that it is a matter of some nicety to get the filaments in their proper position, which is not easily accomplished by the average man, with the result that many of the headlights now in use while provided with adjusting means are very much out of focus due to improper adjustment and resulting in glaring lights which are dangerous and exceedingly annoying to other drivers, when the cars to which they are attached are driven on the highways.

It is one of the objects of this invention, therefore, to provide a headlight in which the necessity for a focusing adjustment is absolutely eliminated and in which a standard bulb may be inserted with the assurance in spite of manufacturing tolerances that its filament will be properly focused.

In driving at night it is very desirable to

have a driving beam with the intensity at the top thereof, and this has been accomplished where a two filament bulb has been used in a short focal length reflector by displacing the lower filament below the axis of the reflector, which throws the intense part of the beam or that part reflected by the portion of the reflector which lies behind the focal plane, upwardly, so that the beam has considerable intensity at the top and shades down to a dimmed light at the bottom. Such a construction has been illustrated in my Patent #1,662,938, dated March 29, 1927. If the focal length of the reflector is increased, the reflector becomes less sensitive to variations of the light source, and hence this effect of a high intensity at the top of the beam becomes lessened as the focal length of the reflector increases. I have found, however, that it is possible to use a reflector having a longer focal length, and still get the high intensity at the top of the beam by providing a lens having certain prisms thereon which are adapted to bend downwardly the light which would normally form the top of the beam. It is, therefore, another object of the invention to provide a lens which may be used in conjunction with a reflector having a relatively long focal length, and which is adapted to bend downwardly certain of the rays projected by the reflector to provide a beam of the desired light distribution.

Another object of the invention is to provide a headlight having such a relation between the focal length of the reflector, the size of the filament, and the configuration of the lens, that a beam of substantially the same outline and cross-sectional intensity will be produced regardless of slight variations in the positioning of the filament.

Another object of the invention is to provide a headlight adapted to project two beams of light, independently of each other, in which the relation between the focal length of the reflector, the distance between the filaments, and the configuration of the lens is such that the angularity between the two beams will not vary substantially regardless of variation of the position of the filaments.

One embodiment of the invention has been

illustrated in the accompanying drawings, in which;

Fig. 1 is a sectional side elevation of a headlight embodying the invention;

Fig. 2 is a front view of the lens shown in Fig. 1;

Fig. 3 is a sectional plan view of the lens taken on the line 3—3 of Fig. 2;

Fig. 4 is a sectional plan view of the lens taken of the line 4—4 of Fig. 2;

Figs. 5 and 6 are sectional plan views of portions of the lens taken on the lines 5—5 and 6—6 respectively of Fig. 2;

Fig. 7 is a diagrammatical view of the projection of light rays from the headlight when the light source is at the focal point of the reflector;

Fig. 8 is a diagrammatical view of the light pattern projected upon a screen in front of the headlight;

Figs. 9 and 10 are diagrammatical views illustrating the direction of the rays projected by the headlight when the light source is above and below the focal point respectively;

Fig. 11 is a diagrammatical view showing the direction of the projected rays when the light source is in front of the focal point; and

Fig. 12 is a view similar to Fig. 11, but with the light source in back of the focal point.

Prior to my invention, the use of a relatively short focal length reflector was almost universal, the focal length being $1\frac{1}{4}$ inches. The standard two-filament light bulb used in such a reflector consisted of two concentrated V shaped filaments having a base approximately $1/16$ " long spaced substantially equi-distant from the axis of the bulb, and approximately $9/64$ of an inch apart. The manufacturing tolerances for these bulbs are plus or minus $3/64$ " for transverse and axial positioning of the filaments and plus or minus $2/100$ " for the distance between filaments. By using this bulb in a short focal length reflector, the slightest variation of either of the filaments from their proper place adjacent the focal point of the reflector resulted in a distortion of the beam which in many cases would render the same unfit for adequate road illumination. By experimentation, I discovered that I could increase the focal length of the reflector to approximately $1\frac{3}{4}$ inches, and by using a compensating lens still project the desired beams at the same time rendering the reflector substantially insensitive to variations of the position of the light source within limits considerably larger

than the tolerances used in manufacturing the light bulbs. In order to accomplish the desired objects of the invention, I have provided a reflector 10 having a relatively long focal length, and in which is mounted a socket 11 adapted to support a light bulb 12 by

means of the usual bayonet slots 13, with the concentrated filaments 14 of the bulb adjacent the focal point 15 of the reflector. The filaments 14 are energized in the usual way, by means of a cable 16 connected to an external source of energy. The reflector 10 is suitably mounted in a casing 17 having a flange 18 to which the flange 19, forming the rim of the reflector, may be attached by means of the screws 20. A lens 21 is held against the flange 19 of the reflector and the connection therebetween sealed by means of the gasket 22. A rim 23 of conventional design holds the lens in place against the gasket and reflector. The lens 21 comprises a disk of glass or other transparent material having a flange 24 slightly offset around its periphery for engagement with the gasket 22 on one side, and the rim 23 on the other, and divided into a plurality of prisms having slight inclination with respect to the vertical plane of the lens. Two of these, the upper prism 25, and the lower prism 26 extend completely across the lens, while the remaining two are positioned in the center of the lens and have the form of a trapezoid, the lower prism 27 forming a base of the trapezoid, and the upper prism 28 completing the upper portion of the trapezoid. At either side of the prisms 27 and 28, the glass is perfectly flat, forming two sections 29 and 30, through which light may project without any vertical refraction. The upper prism 25 starts preferably at the top in a plane with the flat portions 29 and 30 and extends downwardly to the top of the prism 28 at an angle, found in one embodiment of the invention which gave excellent results, to be approximately 2° . The prism 28 at its upper edge is flush with the flat surfaces 29 and 30, and extends downwardly to the upper edge of the prism 27 at an angle of approximately $1\frac{1}{2}^\circ$. The prism 27 starts at its upper edge flush with the surfaces 29 and 30, and extends downwardly at an inclination of approximately 3° , while the lower prism 26 also starts flush with the surfaces 29 and 30, and extends downwardly at an inclination of approximately $1\frac{1}{2}^\circ$. The base of the prism 27 was found to give good results when made approximately $3\frac{1}{4}$ inches wide, while the upper edge of the prism 28 was made approximately $1\frac{1}{4}$ inches wide. The side edges of these two prisms are preferably aligned with each other, as is clearly indicated in Fig. 2 of the drawing.

It will be evident to anyone skilled in the art that in any reflector, no matter which way the filament is moved with respect to the focal point, the light reflected by that part of the reflector lying substantially in a horizontal axial plane, will be bent least in a vertical direction. With a reflector having a relatively long focal point, the reflecting surface which will thus be insensitive to vari-

ations of the light source will be considerably increased in width. In the present invention, I have found by experiment that this insensitive surface may be a little wider than twice the focal length of the reflector, and, as illustrated in Fig. 2, represents the space between the bottom of the prism 25, and the top of the prism 26. The light reflected through this part of the lens, therefore, will form an intense beam A (Fig. 8) and I have provided means to be hereinafter described, so that this beam will form the top of the main beam of light, which is projected down the road. In order to permit this beam to project far down the road, it is essential that the beam be fairly narrow in width, and, therefore, I have provided on the back of this part of the lens, a series of flutes, each flute having a relatively long radius, so that although the beam is spread, which is desirable to avoid shadows it is still kept within relatively narrow limits.

The attainment of the objects of the invention will be best understood by an examination of Figs. 7 and 8 of the drawings in which the projection of light has been illustrated with the light source at the focal point of the reflector. Assuming a single light source 31 to be at the focal point a series of rays *b* are projected through the upper prism 25. As the light source is at the focal point of the reflector, these light rays will be parallel until they strike the lens 21, whereupon the prism 25 bends them down slightly. Another series of rays *e* will be projected through the prism 28 and, similarly to rays *b*, will be bent downwardly. A third series of rays *d* will be projected through the prism 27, and will also be bent downwardly, and a fourth series of rays *c* will be projected through the prism 26 and be given a downward direction. It will thus be seen that all of the rays projected through prisms 25, 26, 27 and 28 are given a downward direction, but inasmuch as these prisms have different inclinations, the rays will be projected downwardly at slightly different angles. Thus, the rays *e* are projected downwardly slightly, and will form a narrow horizontal pattern on a screen in front of the headlight corresponding approximately to the horizontal strip E shown in Fig. 8. I have found by experiment that in order to get the best results and produce a light pattern without holes therein that the prisms should be inclined at the angles indicated above. With the prisms thus inclined, the prism 28 will throw the horizontal strip E just underneath the intense part of the beam A projected through the sides 29 and 30 of the lens. The prism 26 at the bottom will project a group of rays *c* which will form a thin, horizontal pattern C just below the pattern E, the prism 25 at the top will project a group of rays *b* to form a pattern of light B below the pat-

tern C, and the prism 27 having the greatest inclination will throw a group of rays *d* on the screen to form a pattern D at the lower end of the beam. The patterns A, B, C, D and E are only approximately shown in Fig. 8, and it is to be understood that these patterns over-lap and blend with one another, so that the general effect is a horizontal patch of light having a considerably higher bulge at the center thereof, in which the intensity of the light is the greatest. It is to be noted that the chief object for placing the prisms in the lens, as indicated in the drawings, is to project all of the rays which will be substantially affected by variation of the light source below the intense part of the beam A which is projected by the insensitive part of the reflector.

In Figs. 9 and 10, the effect of raising and lowering the filament with respect to the focal point of the reflector has been illustrated. In Fig. 9, source 31 has been shown above the focal point 15 of the reflector, and the full lines indicate the inclination of the rays of light with respect to parallel rays (shown in dot and dash lines) which would be projected if the light source were at the focal point. Inasmuch as the rays pass through the same prisms, they are deflected downwardly, similarly as indicated in Fig. 3, but more so on account of the downward inclination of the rays given by the reflector. The pattern of light, therefore, which is formed by the rays projected, as in Fig. 9, is substantially the same as shown in Fig. 8, but at a slightly lower elevation. In Fig. 10 the rays are indicated as being inclined slightly upwardly, due to the placing of the light source 31 below the focal point 15, and it is evident that inasmuch as the prisms refract the light downwardly, the light pattern will be similar to that shown in Fig. 8, but at a slightly elevated position.

Figs. 11 and 12 show the result of placing the light source in front of and behind the focal plane respectively. When the light source is in front of the focal plane, the rays all tend to converge and the result is that rays *b* and *e* move toward rays *d* and *c*. The contrary is true when the light source is placed behind the focal plane, as illustrated in Fig. 12, wherein the rays are all shown as diverging. In this case, therefore, rays *b* and *e* diverge from rays *d* and *c*, causing patterns B and E to move upwardly, and patterns C and D to move downwardly. It will thus be evident that as the light source is moved with respect to the focal point of the reflector, the patterns B, C, D and E move with respect to each other, sometimes over-lapping more than at other times, but at no time leaving a space between any two of them, which would cause a shadow in the beam, nor do they at any time rise above the intense part of the beam A.

It will be noted that the pattern A is lengthened slightly or shortened as the light source is moved behind and in front of the focal point of the reflector, but that it does not change vertically unless the light source is moved above or below the focal point. If a two filament lamp, therefore, is placed in the reflector with the filaments one above the other, the beams projected independently by these two filaments will be substantially the same regardless of slight variations in the placing of the filaments with respect to the focal point, but one beam will be lower than the other beam depending on the relation between the focal length of the reflector and the distance apart of the filaments.

It is evident from the above that I have provided a headlight which may be adapted to receive in fixed focus a headlight bulb, and which will not be affected by slight variations in the placing of the filament, due to manufacturing tolerances of the bulb, and which at the same time will produce a very desirable beam for driving purposes when one filament is energized, and another beam for driving in traffic declined below the eyes of an approaching driver when the other filament is energized.

My experiments have led me to believe that in order to have the angle between the beams not more than 3 degrees nor less than 2 degrees, the focal length of the reflector should not be more than fifteen nor less than ten and one-half times the distance between the filaments.

In manufacturing lenses as described above I have found that if the angle of a prism is so great that it leaves a relatively great horizontal distance at the bottom of the prism, the lens may warp due to the unequal cooling caused by the non-uniform distribution of glass or the lens may tend to stick to the mold with the result that the inner side of the lens may be slightly concave and this deformation may be avoided by making two or more prisms in the place of the one. This will make no change in the direction of the rays projected as long as the prisms have the same angle, but will merely decrease the thickness of the glass.

In this connection the angularity of the rays due to a given displacement of the filament which must be controlled by these prisms, is much less in the longer focal length than in the shorter focal length reflector thereby requiring less bending power and angle which means less thickness of glass in the prism and less prisms to accomplish the same result, wherefore the present invention considerably simplifies the manufacture of lenses.

The lens described above and illustrated in the drawings is adapted to give proper results when the filaments are spaced substantially equally one above and one below the

axis of the reflector, but if it should be desired to place the bulb in such a position that one filament, for instance, would be substantially at focus and the other above the focus, the angles of the prisms would necessarily have to be slightly increased to accomplish the desired result.

By increasing the number of prisms without changing their angles also provides a means to change the appearance of the lens and to add to this effect the flutes on the rear surface may be made wider or narrower, as desired, so that a large number of lenses may be made having the same light refracting properties but differing in appearance each from the other.

The use of a long focal length reflector produces a more compact beam of light with more even distribution of the intensity thereof over the entire light pattern and hence a more practical and desirable headlight for automobile use.

When a new bulb is inserted in the headlight, it may be found necessary to slightly tilt the headlight casing in order to give the same inclination to the driving beam of each headlight, or, if desired, a small adjustment may be provided for this purpose. This adjustment, it is to be understood, will merely direct the beam, and is in no sense necessary to change the focus thereof.

Many modifications of the invention may be resorted to without departing from the spirit of the invention, and I do not desire to limit myself to the exact arrangement of parts shown in the accompanying drawings and described in the accompanying specification. Only in so far as I have particularly pointed out the invention in the accompanying claims is the same to be limited.

Having thus described my invention, what I claim is:

1. In a headlight, the combination of a parallelizing reflector having a focal length of substantially 1 3/4 inches, a light bulb having two concentrated separately energizable filaments spaced apart substantially 1/8 to 9/64 of an inch located substantially in the focal plane of the reflector adjacent the focus; the focal length of the reflector being not less than 10 1/2 nor more than 15 times the distance apart of the filaments; said reflector being located principally to the rear of the focal plane but having its forward edge slightly in front of the focal plane, means to support the bulb in fixed and non-adjustable relation to the reflector, and a lens having transverse upper, central, and lower zones; the upper and lower zones and the middle portion only of the central zone having prisms thereon to deflect light downwardly; the construction of the headlight being such that the angle of depression between the top of the beams of light produced by the two filaments is not more than 3 degrees nor less than 2 degrees.

2. In a headlight, the combination of a parallelizing reflector having a focal length of approximately 1 3/4 inches, a light bulb having two concentrated separately energizable filaments spaced apart substantially 1/8 to 9/64 of an inch located substantially in the focal plane of the reflector adjacent the focus; the focal length of the reflector being not less than 10 1/2 nor more than 15 times the distance apart of the filaments; said reflector having a reflecting portion located to the rear of the focal plane and having a forward portion extending in front of the focal plane, means to support the bulb in fixed and non-adjustable relation to the reflector, and means to deflect downwardly the rays issuing from the upper and lower zones and the middle portion only of the central zone of the reflector; the construction of the headlight being such that the angle of depression between the top of the beams of light produced by the two filaments is substantially not more than 3 degrees nor substantially less than 2 degrees.
3. In a headlight, the combination of a parallelizing reflector having a focal length of approximately 1 3/4 inches, a light bulb having two separately energizable filaments spaced apart substantially 1/8 to 9/64 of an inch located substantially in the focal plane of the reflector adjacent the focus; the focal length of the reflector being not less than 10 1/2 nor more than 15 times the distance apart of the filaments, said reflector having a primary reflecting portion located rearwardly of the focal plane and having an extension located forwardly of the focal plane, means to support the bulb in fixed and non-adjustable relation to the reflector, and means to deflect downwardly the rays issuing from the upper and lower zones of the reflector; the construction of the headlight being such that the angle of depression between the top of the beams of light produced by the two filaments is substantially not more than 3 degrees nor substantially less than 2 degrees.

In testimony whereof, I affix my signature.
SAMUEL F. ARBUCKLE.

CERTIFICATE OF CORRECTION.

Patent No. 1,826,712.

Granted October 13, 1931, to

SAMUEL F. ARBUCKLE.

It is hereby certified that error appears in the printed specification of the above numbered patent requiring correction as follows: Page 1, line 63, for patent number "1,662,938" read 1,622,938; and that the said Letters Patent should be read with this correction therein that the same may conform to the record of the case in the Patent Office.

Signed and sealed this 15th day of December, A. D. 1931.
